Edwin G. Hatch, Inventor,

By his Attorney
W. B. Hutchinson.

UNITED STATES PATENT OFFICE.

EDWIN G. HATCH, OF HOBOKEN, NEW JERSEY.

INSULATOR-CLAMP.

1,220,333.

Specification of Letters Patent. Patented Mar. 27, 1917.

Application filed May 19, 1916. Serial No. 98,502.

To all whom it may concern:

Be it known that I, EDWIN G. HATCH, a citizen of the United States, and a resident of Hoboken, county of Hudson and State of New Jersey, have invented a new and useful Improvement in Insulator-Clamps, of which the following is a full, clear, and exact description.

My invention relates to insulator clamps such as are used for securing wires to insulators. My invention is especially applicable to insulators carrying high tension line wires or heavy wires, though of course it can be applied to lighter and smaller structures. The insulators are made of different sizes, but where they are supposed to be of the same size they frequently vary in several dimensions. This results from the methods of manufacture, and it is found in practice that there is usually a variation in the neck diameters of the insulators, that the top groove in which the line wire is seated will vary and not always be in the center of the insulator, and that the distance between the bottom of the top groove and the center of the side groove or neck also varies. Furthermore the size of the line wire will obviously be a variable one. The object of my invention is to produce a very simple strong and inexpensive wire clamp which will meet and overcome all the above difficulties, and which is constructed so as to compensate for any of the variations above named, and meet the conditions occasioned by such variations and hold the line wire securely in place. A further and principal object of my invention is to construct the clamp so that it is instantly adaptable to any or all of the above mentioned varying conditions, and under any ordinary circumstances can be quickly secured in place so as to fasten the line wire firmly to the insulator.

Reference is to be had to the accompanying drawings forming a part of this specification, in which similar reference characters indicate corresponding parts in all the views.

Figure 1 is a broken side elevation showing a conventional insulator and my improved clamp applied thereto and to a line wire.

Fig. 2 is a plan view of the same but with the clamp open at one end.

Fig. 3 is a detail section on the line 3—3

of Fig. 4 showing one of the clamping members in inside elevation.

Fig. 4 is a cross section through a line wire and shows a front elevation of one set of clamping members.

Fig. 5 is an outside detail side elevation of one of the clamping members.

Fig. 6 is a view similar to Fig. 5 but shows a slight modification of the invention, and

Fig. 7 is a perspective view of the structure shown in Fig. 6.

In the drawings 10 represents a conventional insulator, and so far as my invention is concerned the insulator may be of any usual or preferred type. Such insulators are usually made, however, with a neck or side 70 groove 11, and with a top groove 12 running across the top in which the line wire 13 is seated. In my construction I use a neck wire 14 which is adapted to extend around the neck 11, that is the side groove of the insulator, and the length of the wire or member 14 is sufficient to cause it to extend with an approximate fit around the neck of a certain size insulator. At its ends the wire is headed as shown at 15 in the hubs 17 of the 80 clamping members or clips 16, and these rise up from the hubs to a point well above the insulator top so that the wire 13 can be clamped between them. The members or clips 16 are vertically slotted as shown at 18 85 to receive a fastening bolt 19, and this can be placed either above or below the wire 13, according to circumstances, and is fastened by a suitable nut. The inner portions of these clips or members 16 are made like the 90 corresponding parts of the sliding clips or clamping members 20 which are arranged on the opposite side of the insulator to clamp the wire 13 in place.

Each member or clip 20 has a hub portion 21 which unlike the corresponding parts in most insulator clamps slides freely on the wire 14. The inside portions of the members 20 are recessed as shown at 22 in Fig. 4, to receive the line wire 13, and it will 100 be noticed that the recess is elongated so that the wire can be quickly and securely clamped without reference to the distance between the center of the neck groove and the top groove 13. At the outer edges the 105 members 20 have meeting flanges 24 which close above the wire 13. The parts are held together by a bolt 25 having a nut 26, and

the body portion of the bolt is preferably squared as shown so as to be more secure. The inner surfaces of the recessed portions 22 of the members 20 are preferably roughed as shown at 23 in Fig. 3, so that they will firmly grip the wire 13.

From the foregoing description it will be seen that without regard to any ordinary irregularities of the insulator, the clamp can be quickly applied to the line wire 13 so as to bind it to the insulator, and it will be further seen that the construction is very cheap and simple. As to its adaptability, it will be noticed that the recess 22 which occurs in both members 16 and 20 provides for the variable distance between the bottom of the groove 12 and the center of the neck groove 11. If the groove 12 is not across the center, it will be seen that the members 20 can be slipped laterally along the wire 14 in the neck groove of the insulator so that that will fit the line wire and hold it as firmly as though the groove were accurately centered. It will be further noticed that the fastening can be effected without any undue strain on any parts of the clamp.

In Figs. 6 and 7 I have shown a slight modification which makes the structure still more adjustable. In this case clamping members 27 and 28 are used, which have hubs 29 sliding on the wire 14, and these members can be used on both sides of the insulator. In this structure the wires 14 near the ends overlap and slide through corresponding holes in the hubs 29 of the members 27 and 28, and when the clamp is adjusted at the right point and the members fastened together, the operator can simply turn up the protruding wire ends with a pair of pliers or the like as shown at 30, thus fastening the clamping members in place.

The members 27 and 28 are generally like those already described, but to provide for a still stronger top connection the member 27 is recessed at the top as shown at 31, and the member 28 has a corresponding lug 32 which fits in the said recess. The members are fastened together as already described.

50 I claim:—

1. An insulator clamp comprising a neck member adapted to fit the neck of an insulator, opposed clamping members at the ends of the neck member adapted to fit a

line wire, and a second pair of clamping members 55 slidable on the neck member and also adapted to fit a line wire.

2. An insulator clamp comprising a neck member adapted to fit an insulator neck, means at the ends of the neck member for 60 clamping a line wire extending across the top and closing the neck member, and means slidable on the neck member for engaging the line wire.

3. An insulator clamp comprising a neck 65 member adapted to fit the neck of an insulator, clamping members at the ends of the neck member rising from said neck member and adapted to engage and clamp a line wire and also close the neck member, and a 70 second set of clamping members slidable on the neck member and rising therefrom, said second clamping members being adapted to engage a line wire.

4. An insulator clamp comprising a neck 75 member adapted to fit the neck of an insulator, closing and clamping members at the ends of the neck member, said clamping members having vertically adjustable means for engaging a line wire, and a second set 80 of clamping members carried by the neck member and also having vertically adjustable means for engaging the said line wire.

5. An insulator clamp comprising a neck member adapted to fit the neck of an insulator, opposed clamping members at the ends of the neck member having recessed inner portions to fit over a line wire, means for fastening the clamping members together, and a second set of clamping members 90 slidable on the neck member and shaped to engage the aforesaid line wire.

6. An insulator clamp comprising a neck member adapted to fit the neck of an insulator, opposed clamping members on the 95 ends of the neck member having vertically adjustable means for engaging a line wire, vertically adjustable means for fastening the clamping members together, a second set of clamping members 100 slidable on the neck member and having vertically adjustable means for engaging a line wire, and also vertically adjustable means for fastening the second set of clamping members together.

EDWIN G. HATCH.
